UNITED STATES PATENT OFFICE.

HOWARD J. SMILEY, OF CANTON, OHIO.

LAUNCHING AND LANDING DEVICE.

1,236,493.

Specification of Letters Patent. Patented Aug. 14, 1917.

Application filed February 29, 1916. Serial No. 81,241.

To all whom it may concern:

Be it known that I, HOWARD J. SMILEY, a citizen of the United States, residing at Canton, in the county of Stark and State 5 of Ohio, have invented certain new and useful Improvements in Launching and Landing Devices, of which the following is a specification.

This invention relates broadly to improvements in flying machine structures, and has 10 particular reference to improvements in devices for absorbing and relieving machines of this character of all shocks and jars encountered during launching or landing operation.

Other objects, as well as the nature and advantages of the invention will appear from a perusal of the following description taken in connection with the accompanying 20 drawings, while the features of novelty of the invention will appear in the appended claims.

In the drawings, wherein is illustrated the preferred embodiment of my invention, 25 Figure 1 is a front elevation of a device constructed in accordance with the invention;

Fig. 2 is a transverse section on the line 2—2 of Fig. 1;

Fig. 3 is a detail perspective of one of the sliding blocks;

Fig. 4 is a fragmentary detail perspective of one of the wheel supporting shafts.

Referring to the drawings by numerals, 1 35 designates the side bars of a suitable frame structure which may be either a portion of the flying machine structure proper or may be a portion of an independent frame for attachment to the flying machine structure. 40 At any rate, a plurality of bars 1 are provided which are arranged in spaced parallel relation and are connected by braces 2.

Arranged below the frame bars 1 and intermediate the same are a plurality of longitudinally spaced alined bars 3 and 5 which are connected and supported by the frame bars 1 by means of braces 4. A single relatively elongated bar 3 is provided intermediate the relatively short end bars 5, a space 50 of any suitable width being provided between the bars 3 and 5, as is illustrated to advantage in Fig. 1 of the drawings, and the bars are arranged in alinement, as shown.

Above the spaces between the bars 3 and 5 and arranged in horizontal alinement

parallel with the bars 3 and 5 are cross-bars 6 of a length to extend slightly over the adjacent inner ends of the bars 3 and 5. Vertically arranged rods 7 have their upper ends 60 journaled in the bars 6 and their lower ends secured rigidly in any suitable manner to the bars 3 and 5, thereby providing increased strengthening means for the device.

Rectangularly shaped blocks 8 are provided which have formed therein openings 9 of a size to receive the ends of shafts 10 upon which the supporting elements, herein shown as wheels 11 are freely rotatable. The shafts 10 are provided adjacent their 70 ends with transverse openings 12 which are adapted to aline with openings 13 in the blocks 8 which extend at right angles to the openings 9, when the shafts are arranged within the openings 9, as is illustrated in 75 Fig. 1 of the drawings. The alined openings 12 and 13 of the shafts and blocks respectively are adapted to receive the vertical rods 7 so that the shafts 10 are vertically movable upon the rods, and at the 80 same time are locked against removal from the blocks and held against rotation.

Expansively acting helical springs 14 are coiled about the rods 7 and have one end abutting the bars 6 and the other end abutting the blocks 8 exerting a tension to normally hold the blocks in engagement with the bars 3 and 5.

Suitable brackets or bearings 15 are secured to and depend from the bars 6, and 90 these brackets have journaled therebetween concaved rollers 16 which are mounted for free rotation, the rollers being disposed directly above the wheels 11, as is shown.

Upon landing of a flying machine 95 equipped with a device as just described, the wheels 11 engaging with the ground, and the weight of the machine bearing upon the frame will cause the blocks 8 together with the shafts 10 and wheels 11 to be moved upwardly upon the rod 7 against the action of the yieldable springs 14, the springs serving to take up the shock which would otherwise occur, as will be understood. When the machine strikes the ground with great force it 100 will be apparent that springs of a tension to take up shocks and jars under ordinary conditions and to be most efficient under all ordinary conditions, would be of insufficient strength to entirely take up all shocks in 105 such an instance. Therefore, the provision of the rollers 16 provides stop means to be

engaged by the wheels in such cases, and by making these rollers rotatable friction is avoided between the wheels and the frame as the same are rotated upon engagement 5 with the ground.

From the foregoing description taken in connection with the accompanying drawings it is thought that the construction and operation of the improved shock absorbing device for flying machine will be clearly understood and while I have herein shown and described one specific embodiment of my invention I do not wish to be limited except for such limitations as the claims may impose.

I claim:

1. A device of the character described comprising a frame, vertically movable supporting elements revoluble on their own axes 20 carried by said frame, and rotatable means on the frame to directly engage the supporting elements and limit their vertical movement but permit rotation thereof.

2. A device of the character described, 25 comprising a frame, supporting elements including ground wheels carried thereby, said supporting elements being bodily movable in a fixed plane, and rotating means mounted on said frame to directly engage 30 the periphery of the wheels of said supporting element and limit movement thereof beyond a pre-determined point in one direction in such fixed plane.

3. A device of the character described 35 comprising in combination with the frame structure of a flying machine, rods carried thereby, supporting elements including ground wheels carried by and longitudinally movable upon said rods, resilient means engaging said supporting elements and tending 40 to force them to their limit of movement in one direction, means to limit any such movement of the supporting elements upon

said rods, and means directly engaging the ground wheels at their limit of movement 45 in the opposite direction.

4. A device of the character described comprising a frame, supporting elements including ground wheels carried by said frame, said supporting elements being bodily movable in a fixed plane and rolling abutments journaled in said plane to engage the peripheries of the wheels and limit their movement in one direction in said plane beyond a pre-determined point. 55

5. A device of the character described comprising, in combination with the frame structure of a flying machine, rods carried thereby, blocks, shafts extending through said blocks, said shafts being provided with 60 transverse openings, said blocks having openings formed therein, said rods being adapted to extend through the aligned openings in the shafts and blocks, and supporting elements loosely mounted on said shafts. 65

6. A device of the character described comprising a frame, rods carried thereby, supporting elements yieldably mounted upon said rods, and rollers carried by said frame to be engaged by the supporting elements. 70

7. A device of the character described comprising, in combination with the frame structure of a flying machine, vertically disposed rods rigidly carried thereby, blocks 75 slidably mounted upon said rods, shafts journaled in said blocks, wheels loose on said shafts, expansively acting springs carried by said rods and engaging said blocks and rollers carried by the frame.

In testimony whereof I affix my signature 80 in presence of two witnesses.

HOWARD J. SMILEY.
